UNITED STATES PATENT OFFICE.

ADOLPH B. LEE, OF OAKLAND, CALIFORNIA.

ELECTRIC SWITCH.

1,109,770.

Specification of Letters Patent. Patented Sept. 8, 1914.

Application filed May 11, 1912. Serial No. 896,681.

To all whom it may concern:

Be it known that I, ADOLPH B. LEE, a citizen of the United States, residing at Oakland, in the county of Alameda and State of California, have invented certain new and useful Improvements in Electric Switches, of which the following is a specification.

My present invention relates to electric switches and comprises a plurality of conductors which must be brought into contact with each other to complete the electric circuit, certain of the conductors being carried by revoluble insulated members arranged in juxtaposed relation to each other.

The device is particularly applicable for use in connection with the sparking system of gas engines, and the principal object of my invention is to provide a device which may be operated only by an authorized person, that is, one familiar with the operation and disposition of the parts of each particular device, inasmuch as the switch is actuated to a circuit closing position by alining certain visible characters on the before mentioned revoluble insulated members, which place the conductors in contact with each other.

Further objects of my invention are to provide a device which is simple in construction, easily applied in connection with existing structures, and one which is inexpensive to manufacture.

In the drawing, forming a part of this specification:—Figure 1 is a front elevation of a device constructed in accordance with my invention, part of the outer casing being broken away to disclose parts of construction. Fig. 2 is a view in elevation of the switching with the central movable member removed. Fig. 3 is a central transverse section through the device embodying my invention. Fig. 4 is a fragmentary section on 4—4 of Fig. 3.

Similar characters refer to similar parts throughout the views.

The device is shown supported by a wall portion 1 of a vibrator box, which has transversely extending bores 2 and 3 formed therein, and the device comprises a base plate 4, having an annular flange 4'; juxtaposed concentric dial member 5 having an annular flange 5' preferably flush at the face with flange 4'; dial member 6 also preferably flush at its face with the face of flanges 4' and 5', all of which are of in-

sulating material, and certain other elements to be subsequently described. The base plate has apertures 8 and 9 formed therein, to be alined with apertures 2 and 3, respectively, of support 1, the aperture 8 being screw threaded. The dial members 5 and 6 have concentrically disposed apertures 5" and 6", respectively, which are alined with apertures 9 and 2, and through which extends a bolt 11 having a head 12, at the end adjacent the dial member 6, a spring washer 13 having fingers 14, being interposed between the head 12 and the dial member 6. On the other end of bolt 11 is turned a lock nut 15, which draws the same to hold all of the dial members in close contact with each other and base 4, but permitting rotation thereof through the slightly yieldable washer 13. By means of washer 16, rigid with the wall portion 1, embracing the bolt 11 next adjacent the nut 15, I electrically connect said bolt with a conductor 17, which may be operatively connected with one pole of the electric generator, (not shown in the drawing), a screw 18, carried by the washer 16, securely holding the conductor in place.

The dial member 6 has embedded therein and exposed at its face, next adjacent to washer 13 and contacting with the fingers 14 thereof, a conducting ring 19 provided with a screw 20 passing to the periphery of the dial member and flush therewith.

Alined to be contacted with screw 20 is a transversely extending conducting mechanism 21 carried by flange 5' and substantially flush therewith at both the internal and external peripheries. The flange 4' carries a conductor 22 alined to be contracted with conducting mechanism 21 through actuation of the dial member 5. The threaded aperture of the base 4 has screwed thereinto a binding post 23 which passes through aperture 3 in support 1 and is, by threaded extension 24, adapted to contact with conductor 22 and the screw may be operatively connected with the other pole of the electric generator through conductor 25.

The conducting mechanism 21 may be composed of two conducting buttons 28 held apart by a compression spring 29, as clearly shown in Fig. 4 of the drawing.

The outer case 30 is screwed to the vibrator case 1 and is provided with an aperture 31 through which the graduation of the dial members 5 and 6 are visible. In order to actuate the dial members 5 and 6 the former

is recessed as at 40 to accommodate a double acting ratchet wheel 32, carried by bolt 11, and pawls 33 and 34 adapted for coaction therewith, being held in contact with ratchet 5 32 by means of springs 35. These pawls are arranged to contact with wheel 32 in opposite directions and pawl 33 is attached to the upper side of dial member 5, while pawl 34 is attached to the under side of dial member 10 6. Thus, when the bolt is rotated in one direction by handle 12, as for instance, in the direction indicated by an arrow in Fig. 2, then dial member 5 is moved and when rotated in a counter direction, dial member 6 15 is moved. To prevent movement of the dial member which is not being actuated by the ratchet, springs 35 are attached to case 30 and press on the upper face of the dial member.

20 The operation of the device is as follows:—The person familiar with the particular device, that is, with the disposition of the contacts with respect to the dial marks, arranges them to engage the contacts 25 and thus completing the circuit through bolt 11, washer 13, ring 19, screw 20, conducting mechanism 21, conductor 22 and binding post 23. As disclosed in the drawing, the relative positions of the contacts are such 30 that the combination, with contacts conductively alined, reads 1—3. .

I claim:—

1. A switch of the character described comprising in combination, a base, a plurality of juxtaposed insulating dial members revoluble with respect thereto, a ring conductor for the uppermost dial member having a lug communicating with the periphery of said dial member, conducting mechanism carried by the dial member intermediate said uppermost dial and said base, a contact alined to contact with said conducting mechanism of the dial member adjacent said base, when said dial member 40 is in a predetermined position with respect thereto, a binding post connected with said last mentioned contact, a washer contacting with said ring conductor, and a binding post operatively connected with said washer, substantially as and for the purpose set forth.

2. In a switch of the character described, the combination of a base provided with an annular flange, a dial member provided with an annular flange and resting within the said flange of said base, a second dial member resting within the said flange of said first mentioned dial member, said dial members being revoluble with respect to each other and to said base, a bolt passing concentrically through said dial members and said base, a contact exposed to the internal periphery of said flange of said base,

conducting mechanism carried by the said flange of said first mentioned dial member and exposed to the internal and external periphery thereof, means exposed at the periphery of said second mentioned dial member and conductively connected with said bolt, and means carried by said bolt for actuating either of said dial members, substantially as and for the purpose set forth. 65

3. In a switch of the character described, the combination of a base provided with an annular flange, a dial member provided with an annular flange resting within the said flange of said base, a second dial member resting within the said flange of said first mentioned dial member, said dial members being revoluble with respect to each other and to said base, a contact exposed to the internal periphery of the said flange of said base, conducting buttons movable transversely through said flange of said first mentioned dial member, a spring interposed 70 between said buttons to expose the same at the internal and external periphery, respectively, of said flange, and circuit closing means at the periphery of said second mentioned dial member, substantially as and for the purpose set forth. 75

4. In a switch of the character described, the combination of a base provided with an annular flange, a dial member provided with an annular flange and resting within the said flange of said base, said dial member having a recess, a second dial member resting within the said flange of the first mentioned dial member, above the said recess therein, said dial members being revoluble 100 with respect to each other and to said base, a revoluble member passing concentrically through the said dial members and said base, a contact exposed to the internal periphery of the said flange of said base, conducting mechanism carried by the said flange of said first mentioned dial member and exposed to the internal and external periphery thereof, circuit closing means at the periphery of said second mentioned dial member, a ratchet wheel carried by said revoluble member, and coacting pawls carried by said first and said second mentioned dial members, and coacting with said ratchet wheel to actuate the same by movement 105 thereof, said ratchet wheel and pawls being disposed in the said recess of said first mentioned dial, substantially as and for the purpose set forth. 110

In testimony whereof I affix my signature 115 in presence of two witnesses.

ADOLPH B. LEE.
